(57) CLAIM

The ornamental design for a multifunctional cosmetic case, as shown and described.

DESCRIPTION

FIG. 1 is a top, rear, left side perspective view of a multifunctional cosmetic case showing my new design, shown in a closed position of use;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof;

FIG. 7 is a rear elevation view thereof; and,

FIG. 8 is a perspective view thereof, shown in an open position of use.

The broken lines depict portions of the multifunctional cosmetic case and form no part of the claimed design.
